UNITED STATES PATENT OFFICE

2,680,596

DETACHABLE FEED LEG STRUCTURE FOR
ROCK DRILLS

James Curtis Houston, Noranda, Quebec, Canada

Application September 12, 1951, Serial No. 246,237

2 Claims. (Cl. 255—52)

1

This invention relates to rock drills and more particularly to detachable telescopic feed leg construction for converting hand-held rock drills to stoper drills.

The term "stoper drill" is a semi-technical term generally applied to a rock drill specially designed to drill vertical or steeply inclined holes and being so designed is not suitable for universal rock drill work. This type of drill is generally of considerable weight and consequently causes undue operator fatigue. Furthermore recent developments in rock drilling have provided carbide-tipped drill rods and carbide insert rock-drill bits which are capable of drilling many feet of rock before reconditioning is necessary. The basic design of present day stopers will not allow sufficient extension of the stoper leg to take full advantage of this new drilling equipment.

A number of devices are now available for converting some types of light-weight rock drill for use as stoper drills. Each has been developed for one specific type of rock drill and is hence not adaptable to universal use. One such device is mounted parallel to the drill but offset therefrom in such a manner that the converted drill is poorly balanced and very difficult to operate. Other devices have a special back head for the rock drill which forms an integral part of the stoper leg so that the rock drill may not easily be converted for drilling flat holes.

It is an object of the present invention to provide a unitary attachment, for converting any ordinary light-weight rock drill to a stoper drill, which is simple in construction and easily and readily attached to or detached from any light-weight rock drill without requiring auxiliary parts or changes in the rock drill itself.

A further object of the invention is to provide a detachable feed leg structure which may be mounted directly in line with any normal rock drill, thus reducing operator fatigue.

The invention will now be described with reference to the accompanying drawings in which:

Figure 1 is a plan view of the converted drill showing the detachable feed leg in section, and

Figure 2 is an elevation view of the converted drill.

In the drawings 1 is a rock drill of any well known type having a chuck 2, a front head 3, a cylinder or body section 4, and a back head 5. Mounted in the back head 5 is the usual throttle valve 6, air inlet 7 and water inlet 8.

The telescopic feed leg in accordance with the invention comprises an outer casing or cylinder 13 having a closure cap 11, a control valve 10

5 mounted on one end of the casing, and a pair of tubular mounting blocks 12 also mounted on said end of the casing. The casing contains a first piston 14 and a second piston 15. Air under pressure is adapted to be supplied to the interior of casing 13 through valve 10 which is the standard type of valve conventionally employed in the supply of air to pneumatic drills. To this end, the valve is provided with the usual air inlet connection 16, air passage 25 communicating with chamber 26, and air passage 27 also communicating with chamber 26 and leading to the interior of casing 13. A hand holding support is mounted on the valve 10 and is rotatable to regulate the air supplied from chamber 26 to passage 27, all in the usual manner. The usual air release passage 28, leading from passage 27 and controlled by button 29, is also provided.

10 The tubular mounting blocks 12 are rigidly secured in parallel relation to the casing 13 and each provides a cylindrical socket 12a for reception of a respective side rod 18. The side rods 18 are of the same diameter and of slightly greater length than the side rods which are standard 15 equipment with the hand held rock drill. The side rods 18 serve to secure the telescopic feed leg 9 to the rock drill 1, as shown. Ends 19 of the mounting blocks 12 abut against shoulders 20 on the back head 5, such shoulders 20 being the conventional side rod-receiving shoulders of a rock 20 drill.

Piston 14 operates within the casing 13 and piston 15 within piston 14.

25 Piston 14 has an end closure 30 and a hollow tubular member 31 extending outwardly therefrom and providing a passage 31a leading to the interior of piston 14. In the retracted position of piston 14, as shown in Figure 1, the passage 31a in member 31 is closed by engagement of the latter with a socket member 32 carried by cap 11. Piston 15 has a closed end 33. In operation, air initially supplied to casing 13 through passage 27 enters space 34 surrounding socket member 32. Such air moves piston 14 outwardly, piston 15 moving outwardly therewith. Since the initial air supply does not enter the interior of piston 14 (passage 31a being closed by socket member 32), piston 15 does not move outwardly with relation to piston 14. When member 31 30 clears socket member 32, air under pressure flows through passage 31a into the interior of piston 14. Normally, the initial air supply is not sufficient to move piston 15 outwardly from piston 14 until the latter is fully extended, when, if desired, an increased supply of air is admitted to the cas-

ing through valve 13 to cause such outward movement of piston 15. A tip 21 is mounted in the outer end of the piston 15.

A tip 21 is mounted in the outer end of the piston 15.

The use of the detachable telescopic feed leg assembly enables any light-weight hand-held rock drill to be easily converted to a stoper drill. The standard side rods (not shown) are removed from the rock drill 1. The telescopic feed leg 9 is placed in axial alignment with the drill 1 so that the mounting blocks 12 seat against the shoulders 23 on the standard back head 5. The extra length side rods 18 are now inserted and tightened and the in-line stoper drill is ready for operation.

The operation of the converted drill is the same as any standard stoper drill. The throttle valve 6 controls the air and water supply to operate the rock drill 1. The control valve 10 is actuated to permit air to enter the feed leg to extend the first extension leg or piston 14 and then the second piston 15 as required depending on the depth of the hole to be drilled.

I claim:

1. In a rock drill having a closed back head and shoulders thereon adjacent said back head, a feed leg structure detachably mounted on said drill and comprising a tubular casing closed at one end and having therein at least one fluid operated member arranged to project from the other end of the casing and having a support-engaging tip on its outer end, means for admitting fluid to the casing to move said member, mounting blocks secured to the casing and each having a socket therein in parallel relation to the casing, each said block also having an end portion projecting beyond said closed end, said end portions abutting said shoulders to maintain

said closed end in spaced relation to said closed back head, and side rods extending through said sockets and securing said feed leg structure to the rock drill.

5 2. In a detachable feed leg for converting a lightweight hand-held rock drill to a stoper drill, a feed leg structure comprising a casing, a cap mounted in and closing one end of the casing, a fluid operated piston mounted in the casing and extending from the other end thereof, said piston having a support-engaging tip on its outer end, means for admitting fluid to the casing to move said piston, said means including a fluid-regulating control valve mounted on the casing adjacent the closed end thereof, and a pair of supporting blocks rigidly connected to and adjacent the closed end of the casing, each said block having a side rod receiving socket in parallel relation to the casing and an end portion projecting beyond said closed end, the ends of said end portions being arranged to abut said rock drill to space said closed end therefrom, and side rods extending through said sockets and arranged to secure said feed leg structure to the rock drill.
